UNITED STATES PATENT OFFICE.

GEORGE M. CLEMENTS, OF KENDUSKEAG, MAINE.

IMPROVEMENT IN CULTIVATORS.

Specification forming part of Letters Patent No. 36,894, dated November 11, 1862.

To all whom it may concern:

Be it known that I, GEORGE M. CLEMENTS, of Kenduskeag, in the county of Penobscot and State of Maine, have invented a new and Improved Cultivator; and I do hereby declare that the following is a full, clear, and exact description of the same, reference being had to the accompanying drawings, making a part of this specification, in which—

Figure 1 is a side view of my invention. Fig. 2 is a plan or top view of the same.

Similar letters of reference indicate corresponding parts in the two figures.

This invention relates to a new and improved implement or device for cultivating crops which are grown in hills or drills, such as corn, potatoes, &c.

The object of the invention is to obtain a device by which the crops may be thoroughly cultivated—that is to say, have the earth at each side of the plants plowed and thrown up to them in a manner similar to that performed by the ordinary hand-hoe.

To this end the invention consists in the employment or use of two plows or shares attached to an adjustable frame provided with gage-rollers, and having the draft-pole and draw-bars attached to it in a novel way, as hereinafter fully shown and described.

To enable those skilled in the art to fully understand and construct my invention, I will proceed to describe it with reference to the drawings.

A represents the frame of the device, which is composed of three bars, a a' , the latter, a' , being the central bar, and attached at its front end by a hinge or joint, b , to a rod, B. The bars a a are also attached by hinges or joints c to the rod B, and the three bars a a' are connected by transverse rods d d , which are permanently bolted to the central bar, a' , and pass through eyes or staples e e , attached to the bars a a , the eyes or staples being drawn up tightly to the rods d d by nuts f , which are fitted on screw-threads, one on the upper end of one of the shanks of each staple. The rods d d are slightly curved, as shown in Fig. 2, so that the side bars, a a , may have a slightly oblique position relatively with the central bar, a' .

C C represent handles, which are attached

at their lower ends to the central bar, a' , by bolts g , and are braced by a support, h , secured on the back part of the bar a' . The rod B has its ends bent at right angles to its main portion, as shown at i i , and the front ends of the parts i are bent in the form of hooks for the purpose of connecting whiffletrees thereto.

D is the draft-pole, which is attached to the rod B; and E is a cross-bar, which is secured to the inner end of the draft-pole, and is bolted at its ends to the parts i i of the rod B. By this arrangement it will be seen that the frame A is allowed to work on the rod B, so that it may be raised and lowered from said rod as a center without affecting the draft-pole and line of draft. To the outer side of each bar, a , there is attached a curved bar, E'. These bars extend downward in front of the bars a a , and terminate in forks k , in which rollers l are placed. The bars E' are perforated each with a series of holes, m , through any one of which a bolt, n , passes into the bars a . The bars E' by this means may be adjusted higher or lower at their front ends.

F F represent two shares, the front ends of which, at their lower edges, are curved inward, so as to resemble an ordinary share. These shares extend backward a considerable distance, being formed of narrow metal plates, and gradually approach each other, a space, o , being left between them, which space is in line with the draft-pole D and central bar, a' , of the frame A, as shown clearly in Fig. 2. The shares F are attached to standards a^x , which are secured to the bars a a of the frame A. As the machine is drawn along a horse walks in each furrow, and a share, F, is at each side of the row, and the earth is plowed up at each side of the row, the curved back ends of the shares drawing the earth up to the plants. The depth of the furrows may be regulated as desired by adjusting the bars E' E' higher or lower, and by depressing the rollers l sufficiently low that the shares F may be raised entirely out of the earth. This adjustment is necessary in transporting the device from place to place.

The frame A, it will be understood, is sufficiently high to pass over the plants without breaking them down or injuring them in any way, and the bars a a of said frame may be

adjusted nearer together or farther apart, as desired, by simply unscrewing the nuts *f* and loosening the eyes or staples *e e*.

Having thus described my invention, what I claim as new, and desire to secure by Letters Patent, is—

The frame *A*, connected with the draft-pole *D*, as described, and composed of three bars, *a a'*, connected together by the rods *d d*, and arranged, as shown, so that the bars *a a* may

be adjusted nearer together or farther apart, as desired, in combination with the shares *F* *F* and adjustable rollers *l l*, all arranged substantially as and for the purpose herein set forth.

GEO. M. CLEMENTS.
